(57) CLAIM

We claim the ornamental design for a bandana, as shown and described.

DESCRIPTION

FIG. 1 is a front elevation view of a bandana, showing our new design in a first configuration lying flat and unfolded; FIG. 2 is a rear elevation view thereof; FIG. 3 is a bottom, front, left perspective view thereof; FIG. 4 is a bottom, front, left perspective view of the bandana, shown in a second configuration with the two sides folded inward;

FIG. 5 is a front elevation view of the bandana, shown in a third configuration with the two sides folded inward;

FIG. 6 is a front elevation view of the bandana, shown in a fourth configuration with the two sides folded inward and the lower portion folded under; and,

FIG. 7 is a top, rear perspective view of the bandana, shown in a fifth configuration with the two sides folded inward, the lower portion folded under and the two straps fastened together.

The broken lines in the drawings show portions of the bandana that form no part of the claimed design.
